MACHINE FOR PICKING FEATHERS
FROM FOWLS

Emmet B. Digby, Atlanta, Ga.

Application November 30, 1945, Serial No. 631,981

5 Claims. (Cl. 17—11.1)

1

My invention relates to new and useful improvements in a machine for the removal of feathers from fowl by mechanical picking or plucking; particularly in the use of a novel rod, a number of which are positioned around the periphery or surface of a revolving drum which presents the rods to the surfaces of the fowl during the picking or plucking operation.

Another object of the present invention is to provide a plurality of rods each of which is flexible and/or pliable and preferably made of natural rubber and provided with a plurality of transversally extending ridges of different heights.

Still another object of the invention is to provide a rod or strip preferably of natural rubber, substantially semi-circular in cross section at its center, and the cross section increasing in depth toward the opposite ends of said rod.

Still another object of the invention is to provide a rod for use in a fowl plucking machine, the rod having a plurality of transversally extending ridges extending from the one side of the rod over to the other side; the bottom of the rod being flat and the thickness of the rod increasing from its center towards the opposite ends.

Still another object of the invention is to provide flexible and pliable rods to be mounted at their opposite ends to a rotating drum, the rods presenting an arcuate frictional surface, and the center of the arcs being more flexible than the remaining portions thereof.

Still another object of the invention is to provide a flexible rod flat on its bottom, circular on its top and varying in thickness from its ends towards the center, the greater portion of the rod being provided with spaced ridges, the highest of which are located centrally of the length of the rod.

Still another object of the invention is to provide a plurality of rods each of which is provided at its opposite ends with enlarged pads or feet so that the feet may be fitted into spaced apertures in the drum, the said rods projecting outwardly from the drum in an arcuate and substantial semi-circular position.

Still another object of the invention is to provide a rod having projecting feet which may be quickly applied to spaced apertures formed in a metal drum by turning or twisting the rods so that they are normally tightly held in position but may be quickly removed by again revolving or turning the feet within the apertures.

With these and other objects in view the invention consists in certain new and novel arrangements and combination of parts as will be herein-after more fully described and pointed out in the claims.

Referring now to the drawings showing a preferred embodiment:

2

Fig. 1 is a vertical sectional view of the stand in which the rotary drum and its rods are located;

Fig. 2 is a fragmentary top plan of the drum showing the staggered arrangement of the rods;

Fig. 3 is an enlarged side elevation of one of the rods as mounted in the drum;

Fig. 4 is a sectional view taken on line 4—4 of Fig. 3;

Fig. 5 is a side elevational view of the rod before being fastened to the drum;

Fig. 6 is a top plan view thereof;

Fig. 7 is a view of one of the feet on the end of the rod;

Fig. 8 is a cross sectional view taken on line 8—8 of Fig. 5;

Fig. 9 is a cross sectional view taken on line 9—9 of Fig. 5;

Fig. 10 is a cross sectional view taken on line 10—10 of Fig. 5; and

Fig. 11 is a fragmentary top plan view of a portion of the drum showing the staggered apertures for the reception of the rods.

Referring now to the drawings and for the moment to Fig. 1 there is shown a conventional stand 1 in which is mounted a rotary drum 2, which will be driven by a motor 3 mounted on the top of the stand. There also may be seen the top 4 with a door 5 beneath the top so that any feathers that lodge under the table may be easily removed. The door may be hinged as at 6. Also there will be the ordinary hood 7 extending over the drum.

In the drum 2 there is shown a supporting spider 8 together with a driven shaft 8a, there being several of the supporting spiders. The internal structure of the drum forms no part of the present invention, but the arrangement of the outer wall of the drum is important. This wall is provided with a plurality of transversally extending rectangular slots 10 arranged to cooperate with special feet or pads 11 on the ends of the rods 9 which latter also form an important part of the invention.

These apertures 10 are spaced circumferentially about the drum in rows and the apertures in one row will be in staggered relationship with the apertures in the adjacent row, thus the end of one rod 9 will appear about opposite the center portion of the adjacent rod.

It will be noticed that these apertures 10 have their long dimensions extending transversally of the drum, so that the pads or feet 11 on the ends of the rod 9 shortly to be mentioned, may be slipped in place by positioning the feet parallel with the long dimensions and turning the rods 90° so that after the rods are once in place they cannot be removed again until the feet 11 of the rods are turned parallel with the long dimensions of the apertures.

Now referring to Figs. 3 to 10 inclusive there is shown in detail, one of the rods and the manner

in which it is secured for quick removal to the drum.

As all of the rods are identical, a description of the one is a description of all. As heretofore mentioned, the rod is preferably formed of rubber of such elasticity or flexibility, that when in the arched position, as shown in Fig. 3, it will bend or yield under pressure; in other words, be depressed slightly or flattened so that it will not tear the skin of the fowl from which the feathers are to be removed.

Naturally, the amount that each rod flexes or depresses will depend upon how hard the operator presses the fowl against these rotating rods.

It will also be noticed that the rod 9 is provided with a flat under surface 12 and a semi-circular top surface at its central portion as shown by Fig. 10.

It will also be noticed from Figs. 5, 8, 9 and 10 that the surface contour of the rod changes as the outer ends are approached as well as the depth or thickness of the rod. In other words, due to the arcuate under surface of the rod, the thinnest portion of the rod is at its center as shown in Fig. 10, thicker as it approaches its end as shown in Fig. 9 and thickest at its outer ends as shown in Fig. 8. Thus, when the rod is attached as shown in Fig. 3 the central portion is the portion that is most easily depressed or flattened.

Also it will be noticed that the rod 9 is provided with a plurality of transversely extending ridges which simulate screw threads but are not in helical formation.

It will also be noticed that centrally of the rod appears the highest ridge or projection 13 and on the opposite sides of the central ridge 13 may be other ridges 14 of slightly less height while the remaining ridges 15 may or may not be all of the same height.

In actual practice the rods are about 8 inches in length and these ridges occupy about 5 inches of the length of the rod so that a maximum of ridges or frictional surfaces are presented against the irregular surface of the fowl being picked or plucked as the rods are depressed. From this it will be seen that when the rods are all in their position on the drum, the fowl when being plucked is at all times in contact with most of these transversely extending ridges, so that the time for picking or plucking the fowl is reduced to a minimum.

Also in actual practice the angle of the ridges of the rods is 60° so that relatively sharp surfaces are presented to the fowl in the plucking operation.

As it will be appreciated, the highest ridges, that is, those as shown at 13 and 14 will take off the larger or outer feathers and the small ridges will remove the smaller or pin feathers.

Also it may be mentioned in actual practice that the largest ridge 13 is preferably one-quarter of an inch in height while the ridges 14 may be three-eighths of an inch and the next ridges may vary from one-eighth to one-sixteenth of an inch as desired.

Near the opposite ends of the rod 9 and adjacent to the inner surfaces of the feet or pads 11 may be seen the small grooves 16 from which extend the upper ends 17 of the feet or pads 11. These feet also both extend at an angle from the vertical as may be seen in Fig. 5 as heretofore mentioned. The height of the feet 11 is greater than the short dimension of the rectangular openings 10 and equal to the longer dimensions

of the rectangular openings 10 so that by turning the foot parallel with the long dimension of the opening 10, it may be quickly inserted and afterwards turned so that it cannot work loose or be removed unless turned by the operator.

These rods wear out relatively quickly in service and by providing the feet 11 and the rectangular openings 10 in the drum as shown, it is but the matter of a moment to grasp a broken or damaged rod, turn first one foot and then the other and then remove the rod. To replace a rod the operations is just reversed.

From the foregoing, it will be seen that I have produced a plucking or picking machine for fowl that will operate in an efficient and quick manner to remove the feathers, and I have found in actual practice, that an operator can remove the feathers in about five seconds from each fowl.

Having thus described my invention what I claim is new and desire to secure by Letters Patent is:

1. A rod for a fowl picking machine formed of flexible material semi-circular in cross section at its center, the cross section increasing in depth towards the opposite ends of said rod, projections on the outer surface of the rod and extending substantially transversely of the rod, said projections being of varying height, and the highest of the projections being in the semi-circular section of said rod.

2. A rod formed of flexible material for a fowl picking machine, the rod having a flat bottom side extending transversely of the rod and the said bottom side being arched longitudinally of the rod to thereby provide a relatively thin central portion, and transversely extending ridges of varying height on the outer surface of the rod, the highest of the ridges being centrally of the rod.

3. A rod formed of flexible material for a fowl picking machine, the rod decreasing in thickness from its ends towards its center, transversely extending ridges about the outer surface of the rod, and feet formed on the opposite ends of the rod adapted to interlock with cooperative recesses in a rotatable drum.

4. A rod formed of flexible material for a fowl picking machine, the rod decreasing in thickness from its ends towards its center, thread-like projections extending about the outer surface of the rod, integral feet angularly positioned at the opposite ends of the rod and the height of the feet being greater than their width.

5. A flexible rod for use in a fowl picking machine, said rod being thinnest at its center and thickest at its opposite ends, the said rod provided with thread-like portions extending throughout the greater portion of the rod, the said thread-like portions being of varying height, and feet on the opposite ends of the rod for interlocking engagement with a support.

EMMET B. DIGBY.
